(57) CLAIM

The ornamental design for footwear, as shown and described.

DESCRIPTION

FIG. 1 is a front perspective view of footwear, embodying my new design;

FIG. 2 is a left side view thereof;

FIG. 3 is a right side view thereof;

FIG. 4 is a front view thereof;

FIG. 5 is a top view thereof;

FIG. 6 is a front perspective view of a second embodiment of footwear, embodying my new design;

FIG. 7 is a left side view thereof;

FIG. 8 is a right side view thereof;

FIG. 9 is a front view thereof;

FIG. 10 is a top view thereof;

FIG. 11 is a front perspective view of a third embodiment of footwear, embodying my new design;

FIG. 12 is a left side view thereof;

FIG. 13 is a right side view thereof;

FIG. 14 is a front view thereof; and,

FIG. 15 is a top view thereof.

The broken line showing of the sole, heel, toe thong, footbed, straps, and circular pieces is for illustrative purposes only and forms no part of the claimed design.
